UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

RAILWAY SIGNAL LANTERN.

Application filed April 5, 1920. Serial No. 371,295.

To all whom it may concern:

Be it known that I, REUBEN B. BENJAMIN, a citizen of the United States, residing at Chicago, in the county of Cook and State of Illinois, have invented new and useful Improvements in Railway Signal Lanterns, of which the following is a full, clear, concise, and exact description, reference being had to the accompanying drawing, forming a part of this specification.

My invention relates to lighting devices and more specifically to railway signal lanterns.

One of the objects of my invention is to provide an improved lighting device which can be easily and quickly attached and detached.

A further object of my invention is to provide an improved lighting device which can be attached in various positions.

A further object of my invention is to provide an improved lighting device which will be durable and efficient in use, simple in construction and cheap to manufacture.

Further objects will appear from the detailed description to follow and from the appended claims.

In the drawings in which two embodiments of my invention are shown:

Fig. 1 is an axial section of a railway signal lantern on the line 1—1 of Fig. 2;

Fig. 2 is a plan view of the lantern and part of a connection shown in Fig. 1;

Fig. 3 is a bottom plan view of that portion of the device which stays in place;

Fig. 4 is a section on the line 4—4 of Fig. 2;

Fig. 5 is a perspective view of a switch arm;

Fig. 6 is a fragmentary sectional view of the outer part of the lantern;

Fig. 7 is a bottom plan view of the lantern;

Fig. 8 is a fragmentary axial section showing a modification in which the lantern is not provided with a switch;

Fig. 9 is a fragmentary plan view of the detachment; and

Fig. 10 is a top plan view of the lantern receptacle and a portion of the supporting bracket.

The construction shown comprises in a general way a permanent portion which remains in place on the locomotive, comprising a wiring base 10 and center and side con-

tacts 11 and 12, and a detachable lantern, comprising a lamp receptacle 13, having center and side contacts 14 and 15 respectively, for quick detachable engagement with respect to the center and side contacts 11 and 12 respectively, and a casing 16 for housing the receptacle 13 in the upper part thereof and a lamp 17 supported within said casing.

The detachable lantern has a sort of bayonet joint connection with the part of the device which remains in place, the lantern for this purpose being provided with a handle portion 18 (Figs. 1 and 7) surrounding the opening in the casing 16 through which the lamp 17 is inserted and removed.

For inserting and removing the lamp 17, the bottom 19 of the casing is provided with a hinged door 20. In order to turn the light on or off, the receptacle 13 is provided with a switch mechanism 21 having an operating button or handle 22, which projects through the bottom of the casing, so as to be accessible for operation.

In order that the detachable part of the lantern may be connected to the permanent part in various positions of rotatable adjustment, the bayonet joint connection is so made that the connection may be effected in four different positions at 90 degrees apart. The casing is provided with a plurality of lenses (two are shown) 23 and 24, which lenses may be of any desired color suitable for signaling purposes. The lantern may be attached so that any lens may be at the top, bottom, or at either side.

For effecting the bayonet joint connection between the removable and the stationary part, the stationary part is provided with four posts or buttons 25 for engagement respectively with the four key-hole slots 26 in the upper part of the casing 16.

In order to center the casing with respect to the permanent part of the device, the housing member 27 of the permanent part of the device is provided with an annular flange 28, which surrounds and receives the cylindrical portion 29 of the casing 16. This centers the casing with respect to the housing 27 and assists in guiding the parts together so that the buttons 25 will properly engage the enlarged portions of the bayonet or key-hole slots 26.

In order to hold the casing 16 in place within the housing 27 after the bayonet

- joint connection has been effected, an annular latching member 30 is provided, having four holes through which the posts or buttons 25 extend, and provided with four 5 coil compression springs 31, for yieldingly holding this latching member in engagement with the inner end of the housing 16. The spring pressed latching ring 30 is provided with means for preventing the casing 10 16 from twisting after it has been rotated into place, these means comprising four downwardly pressed straps 32, pressed out of the material of the latching ring, which ride down into the enlarged portions of the 15 keyhole slots 26 when the casing 16 is rotated to effect the bayonet joint connection. In order that the latching ring 30 will not have to be forced inwardly when the casing 16 is first in position to make the 20 bayonet joint connection, the upper end of the casing 16 is depressed at four points, as indicated at 33, corresponding to the depressed portions 32 of the latching ring, the depressed portions 33 being located so 25 that when the casing 16 is first presented for making the bayonet joint connection, the depressed portions 32 of the latching ring will enter the depressions 33 of the casing, so that it will not be necessary to 30 force the latching ring inwardly when the casing is first brought into position to make the bayonet joint connection. For the same purpose the buttons or posts 25 are provided with annular shoulder portions 34 35 which are engaged by the latching ring 30, so that this latching ring cannot come clear out to the heads of these posts, but the key-hole bayonet joint slots 26 are large enough so that they can receive these shoulders 34, 40 so that the edge of the key-hole slot can slip between the head of the button or post 25 and the latching ring 30.
- The edges of the key-hole slots 26 are 45 made inclined, so that as the casing 16 is rotated to make the bayonet joint connection it will also be gradually forced inwardly, to cause a good contact to be made between the contacts 14 and 15 of the detachable portion with the contacts 11 and 12 of the 50 wiring base. Coming now to the detail construction of the wiring base, this comprises an insulating base 35 on which the center and side contacts 11 and 12 are mounted, and wiring terminals 36 and 37 respectively 55 for the contacts 11 and 12. The insulating base is secured in the housing 27 by means of a pair of screws 38. Openings 39 are provided in the wiring base for the feed wires which are led into the housing 27 60 through the conduit 40. The side contacts 12 are located on opposite sides of the center contacts 11 in position to engage the annular side contact 15 on the detachable receptacle 16.
- 65 The switch receptacle 13 comprises a two-

part insulating base on the inner part 41 of which are mounted the center and side contacts 14 and 15 respectively, the center and side contacts 42 and 43 of the receptacle or socket, and the switch mechanism 21. The outer base portion 45 serves as a cover for the switch mechanism and as a housing for the receptacle contact, the two parts of the base being secured together by means of screws 46.

70 The switch mechanism 21 itself may be of any suitable type, and as shown comprises a snap toggle switch having a pivoted switch arm 47 and an actuating lever 48 which is connected with the button 22 by means of a link 49 (Fig. 4). In order to relieve the switch mechanism from undue strain, a yielding connection is provided between the button 22 and the link 49, this yielding connection comprising a coil compression spring 50, one end of which bears against the shoulder portion 51 on the link 49 and the other end of which exerts an outward force on the button 22. The outer end of the link 49 is 75 embedded in a bushing or sleeve 53, secured to the bottom of the casing 16, this sleeve also serving as a guide for the button 22.

80 The switch arm 47 comprises, as shown in Fig. 5, a pivoted U-shaped arm 54, which may be a sheet metal stamping, and another sheet metal stamping 55, which is bent to form two U-shaped contact members 56 which straddle the arms of the U-shaped member 54, and a connection member 57 which extends across the edge of the connecting part of the U-shaped member 54, the arms of the U-shaped connecting member 54 having lugs 58 struck inwardly therefrom for engaging the edge of the U-shaped contact piece 56. The lug 58, in connection with the cross piece 57, holds the member 55 securely in position on the U-shaped member 54. The door 20 is connected to the bottom 19 of the casing, by means of bent tongues 59, which extend through openings 60 in the bottom 19 of the casing and are looped around strap portions formed integral with the bottom of the casing 19. A strap handle 60^a is provided for the door 20. A spring latch 61 is secured to the casing and engages the edge of the door to hold it in enclosed position.

85 In use, if the detachable portion is disconnected from the portion which stays in place, and it is desired to connect up, the casing 16 is brought into the desired position for making the bayonet joint connection and given a slight turn sufficient to permit the latching member 30 to move into latching position. As previously stated the lantern can be connected in any one of four different positions, as any one of the bayonet slots 26 can engage any one of the four buttons 25. The lamp can be turned 90 on or off by operating the button 22, and the

lamp may be removed from the casing through the door 20.

The circuit is from the wiring terminal 36 through the wiring base contact 11, center contact 14, receptacle center contact 42, lamp 17, shell contact 43, switch 21, annular side contact 15, side contact 12 to the wiring terminal 37.

The switch mechanism 21 controls the circuit between the shell receptacle contact 43 and the annular side contact 15, the arm 47 of the switch being movable into and out of engagement with the contact pieces 62 and 63, the contact 62 being electrically connected with the annular side contact 15, and the contact 63 being electrically connected with the shell receptacle contact 43, as shown in Fig. 2.

In Figs. 8 and 9 the construction is substantially the same as in the form just described, except that the switch mechanism is omitted, the receptacle base 64, which supports the contact 14 and the shell contact 43 being made in one piece. Otherwise the construction is substantially the same, the casing 16 being inserted within the flange portion 28 of the housing 27, and connected with the four buttons 25, the latching ring 30 engaging the housing 16 to hold the bayonet joint in connected position, the center and side contacts 14 and 16 of the receptacle engaging the center and side contacts 11 and 12 of the wiring base respectively, and the circuit being from the center contact 11 through the center contact 14 through the lamp 17 to the shell contact 43 and thence to the side contact 15 and to the side contact 12.

The housing member 27 of the permanent part of the device may be secured to the locomotive in any suitable manner, as by means of screws 65 (Fig. 10) extending through registering openings in the bottom of the casing 27 and the supporting bracket 66, the supporting bracket 66 being secured in any suitable manner to the locomotive.

Having thus described my invention, what I claim as new and desire to secure by Letters Patent is:

1. A railway lighting device comprising a permanently installed lantern supporting part, and a lantern, said lantern comprising a casing for the lamp, an electric lamp socket in said casing, said casing being provided with a plurality of bull's-eyes, means whereby said lantern may be connected with respect to said permanent part in different positions of rotative adjustment, whereby said bull's-eyes may be displayed in different positions, said permanent part being provided with center and side contacts, said lantern also having center and side contacts for engaging the permanent contacts, said connecting means comprising a bayonet joint, all of said contacts and said bayonet joint lying substantially in the same plane,

said bayonet joint being coaxial with said center contact.

2. A railway lighting device comprising a permanently installed lantern supporting part, and a lantern, said lantern comprising a casing for the lamp, an electric lamp socket in said casing, said casing being provided with a plurality of bull's-eyes, means whereby said lantern may be connected and disconnected with respect to said permanent part in different positions of rotative adjustment, whereby said bull's-eyes may be displayed in different positions, said socket being mounted in one end of said casing, and a door in the opposite end of the casing for the insertion and removal of the lamp, said bull's-eyes being mounted on that part of the casing between the socket and door.

3. A railway lighting device comprising a permanently installed lantern supporting part and a lantern, said lantern comprising a casing for the lamp, an electric lamp socket in said casing, said casing being provided with a plurality of bull's-eyes, means whereby said lantern may be connected and disconnected with respect to said permanent part in different positions of rotative adjustment, whereby said bull's-eyes may be displayed in different positions, said socket being mounted at one end of said casing, said casing being provided with a hand-hole member at the opposite end of said casing for use in connecting and disconnecting said lantern with respect to said permanent part.

4. A railway lighting device comprising a permanently installed lantern supporting part and a lantern, said lantern comprising a casing for the lamp, an electric lamp socket in said casing, said casing being provided with a plurality of bull's-eyes, means whereby said lantern may be connected and disconnected with respect to said permanent part in different positions of rotative adjustment, whereby said bull's-eyes may be displayed in different positions, said socket being mounted in one end of said casing, and a door in the opposite end of the casing for the insertion and removal of the lamp, said bull's-eyes being mounted on that part of the casing between the socket and door, said casing being provided with an annular hand-hole member surrounding said door, said door being accessible through said annular hand-hole member.

5. A railway lighting device comprising a permanently installed lantern supporting part, and a lantern, said lantern comprising a casing for the lamp, an electric lamp socket in said casing, said casing being provided with a plurality of bull's-eyes, means whereby said lantern may be connected with respect to said permanent part in different positions of rotative adjustment, whereby said bull's-eyes may be displayed in different positions, said permanent part being

provided with center and side contacts, said lantern also having center and side contacts for engaging the permanent contacts, said connecting means comprising a bayonet joint, all of said contacts and said bayonet joint lying substantially in the same plane, said bayonet joint being coaxial with said center contact, said bayonet joint connection comprising a plurality of headed pins 10 mounted on said permanent part extending parallel to the axis of said socket, and a plurality of slots in the end of said casing for cooperation with the heads of said pins.

6. A lighting device comprising a permanent lantern supporting part, a part having a quick detachable engagement with said permanent part, said permanent part comprising an insulating base, wiring terminals mounted thereon, contacts also mounted 15 thereon, said quick detachable part comprising contacts for quick detachable engagement with said first contacts, a lamp receptacle, a casing for enclosing the lamp in said receptacle, said quick detachable con-

nection comprising a bayonet joint, a plurality of buttons engaging the bayonet slots in the upper part of the casing, and a latching ring slidably mounted on said buttons.

7. A lighting device comprising a permanent lantern supporting part, a part having a quick detachable connection with respect to the permanent part, the permanent part comprising wiring terminals and contacts, the quick detachable part comprising a lamp receptacle and contacts for quick engagement with respect to said first contact, a switch mechanism, a casing for the lamp in said receptacle, said casing having a door at the bottom for the insertion or removal 35 of the lamp with respect to the casing, and said switch mechanism having an operating member extending through said bottom in accessible position.

In witness whereof, I have hereunto subscribed my name.

REUBEN B. BENJAMIN.
